UNITED STATES PATENT OFFICE.

EMORY HAMMETT LORD, OF WASHINGTON, DISTRICT OF COLUMBIA.

MEASURING DEVICE.

1,422,112.

Specification of Letters Patent. Patented July 11, 1922.

Application filed March 4, 1920. Serial No. 363,352.

To all whom it may concern:

Be it known that I, EMORY HAMMETT LORD, citizen of the United States, residing at Washington, District of Columbia, have 5 invented certain new and useful Improvements in Measuring Devices, of which the following is a specification.

The present invention relates, primarily, to improvements in measuring devices and, 10 more particularly, to an improved device designed for use in handling butter, lard, ice cream, etc., and wherein the material handled can be measured for instance, in one pound quantities, provision being made to 15 compensate for the varying consistency of the material handled due to variations in temperature.

The principal object of the invention is 20 to provide a light and durable device of the above character which may be produced in different sizes, for instance, one and two pound quantities, to supplant the ordinary paddle used in handling butter, lard, etc., and which upon being thrust into the material 25 in practically the same manner as the ordinary paddle will gather only a certain quantity of the material, one or two pounds according to the size of the device thus eliminating a second measuring of the material as would be the case if the ordinary 30 paddle were used.

A further object of my invention is to provide means for varying the capacity of the container so as to compensate for the varying 35 consistency of the material handled due to differences in temperature, it being well known that material such as butter or lard varies in consistency due to heat and cold.

A still further object of the invention is 40 to provide means for ejecting the contents of the device after a sufficient quantity of material has been provided therein.

Various other objects and advantages of 45 my invention will become apparent during the continuance of the following description.

In the drawings:

Figure 1 is a view in longitudinal cross section showing my device as in its preferred embodiment, the plunger being shown 50 in an extended position.

Figure 2 is a view similar to Figure 1 showing the plunger in its rearmost position.

Figure 3 is a view in transverse cross section taken on line 3—3 of Figure 1.

Figure 4 is a view in longitudinal cross section taken on line 4—4 of Figure 1, and

Figure 5 is a view in transverse cross section taken on line 5—5 of Figure 2.

The device of my invention consists generally of a body or container portion 10 of a certain predetermined size, open at its forward end as at 11 and provided with a central opening 12 in its rear end as clearly shown in Figure 1. The body may be constructed of any suitable or desirable material.

A handle portion 13 is positioned upon the rear end of the body 10 as at 14 and is provided with a longitudinal recess 15 open to the opening 12 of the body portion. Near its rear end the walls of the recess 15 are constricted as at 16 and finally terminate in a recess 17 of much smaller diameter than the recess 15 and slightly smaller in diameter than the opening 12 of the body portion. The handle may also be constructed of any suitable or desirable material.

I also provide a plunger head 18 which 80 operates within the body portion 10 and which is provided with guide lugs 19 which seat and operate in the longitudinal guide ways 20. Upon reference to Figure 2 it will be noticed that the guide ways terminate 85 short of the open end of the body portion so as to limit the forward movement of the plunger head and prevent the same being forced through the open end of the body portion as might otherwise happen.

A plunger rod 21 carries the head 18 and extends through the opening 12 into the recess 15 of the handle 13. When the plunger head 18 reaches its rearmost position as shown in Figure 2 the rear end of the plunger rod will have been guided into the recess 17 and thus it will be firmly held against lateral movement. An expansion spring 22 is positioned about the rod 21 one end bearing against the head 18 and the other end against the rear end of the body portion 10. This spring is of sufficient strength to force the head 18 to its forward position and dislodge the material in the body portion. When the plunger 18 reaches its rearmost position the 105 spring is compressed as clearly shown in Figure 2.

The body portion 10 is further provided,

near its rear end, with a longitudinal slot 23 through which projects a standard 24 that is carried on a plate 25. The plate 25 lies outside the body portion 10 between the 5 outer face of the body portion and a guide member 26. A pawl 27 is pivoted on the standard 24 as at 28 and is held in position by means of a tension spring 29 that is carried upon the plate 25. The plate 25 is 10 also provided with an upstanding guide lug 30 that projects through the slot 23 of the body portion and lies adjacent the free end of the pawl 27.

In order to regulate the standard 24 so as 15 to vary the capacity of the body 10 I provide an adjusting screw 31 which operates through a bushing 32 in the rear end of the body 10 and which is loosely connected to the standard 24 as at 33. Consequently upon 20 manipulation of the adjusting screw the standard 24 and the plate 25 may be moved forwardly or rearwardly with respect to the body portion 10.

In order to operate the pawl 27 I equip 25 the handle 13 with an adjustable yoke 34 upon which is pivoted as at 35, an operating lever 36. The operating lever has one end connected with a pawl 27 by means of a cable or other connecting means 37 where- 30 by upon actuation of the lever 36 the pawl will be moved against the tension of the spring 29. Means such as shown at 38 may be provided so that the yoke 34 can be held in certain adjusted positions on the handle 35 13 in accordance with the adjustment of the standard 24 and the plate 25.

A fixed pawl 39 is carried on the plunger head 18 in alinement with the pawl 27 above referred to. Consequently when the plunger 40 18 is moved to its rearmost position as shown in Figure 2 the pawls 27 and 39 will be interlocked thus retaining the plunger in a fixed position until the pawl 27 is released by means of the operating lever 36.

45 In operation the body portion 10 is thrust into the tube or keg of material. The material entering the body portion will force the plunger 18 rearwardly until the pawls 27 and 39 will become engaged. The device 50 is then withdrawn, the operator simply presses the lever 36 and the material within the body portion is ejected by action of the spring 22 forcing the plunger outwardly.

What is claimed is:

55 1. In a measuring device, a container portion open at one end, a handle, a plunger movably mounted in said container portion, means to yieldingly retain said plunger normally in its forwardmost position, means 60 carried by said container portion to limit the rearward movement of said plunger, and said last-named means being adjustable to vary the limit of backward movement of said plunger.

65 2. In a measuring device, a container por-

tion open at one end, a handle portion hollow throughout a portion of its length, said container portion being provided with an opening alined with said hollow portion of said handle, a plunger head movably 70 mounted in said container portion, a rod carried by said plunger head positioned through said opening and extending into said hollow portion of said handle, said container portion provided with longitudinal guide-ways, lugs on said plunger head operating in said guide-ways, an arm on 75 said plunger head, means to yieldingly retain said plunger head in its foremost position with respect to said container portion, 80 a standard positioned in said container portion behind said plunger head, a pawl on said standard adapted to engage said arm when said plunger reaches its rearmost position to retain said plunger head in such 85 position, means to release said pawl to allow said plunger head to move forward, and means to adjust said standard longitudinally with respect to said container portion 90 to change the limit of rearward movement of said plunger head as and for the purposes described.

3. A measuring device comprising tubular scoop open at one end and having a hollow handle adjacent the other end, an ejector 95 movable between the open end and handle end of the scoop, said means including a plunger head movable longitudinally of the scoop and a rod carried by the plunger and in line with the hollow handle, the latter 100 serving to house the said rod when the head is at the handle end of the tube, means at the inner end of the scoop for releasably retaining the ejector adjacent the handle end and means for forcing the ejector outwardly 105 of the scoop when released.

4. A measuring scoop comprising a scoop barrel, means for ejecting the contents of the said barrel and including a member 110 movable inwardly of the barrel by pressure of material forced therein, means for stopping the inward movement of the said member, said means being adjustable longitudinally of the barrel for varying its point of contact with the said member to either 115 enlarge or diminish the capacity of the barrel, means for automatically locking the member to the stop-means upon their mutual engagement, means for releasing the lock, and means for automatically forcing the 120 member, when released, outwardly to eject the material.

5. A device of the character specified comprising a container provided with a slot, a spring-thrust plunger operating longitudinally within the container, a longitudinally extending guide on the outer face of the container, a plate slidably in the guide and having an integral portion projecting inwardly through said slot in the container 125 130

to lie in the path of the plunger, said portion constituting a stop for limiting the inward movement of the plunger, means for adjusting the said plate longitudinally of the 5 guide for varying the position of the stop-portion whereby the capacity of the container may be enlarged or diminished, a lug carried by the plunger, a locking mem-

ber carried by the stop-portion for engaging the lug to hold the plunger inwardly of the 10 container and means for releasing the plunger for movement outwardly of the container to eject the contents thereof.

In testimony whereof I affix my signature.

EMORY HAMMETT LORD.
